DESIGN FOR A RAZOR

Lucy Cotton, Miami, Fla.

Application December 30, 1944, Serial No. 117,198

Term of patent 14 years

(Cl. D22—3)

To all whom it may concern:

Be it known that I, Lucy Cotton, a citizen of the United States, residing at Miami, in the county of Dade and State of Florida, have invented a new, original, and ornamental Design for Razor, of which the following is a specification, reference being had to the accompanying drawing, forming part thereof.

In the drawing:

Fig. 1 is a perspective view of a razor, showing my new design.

Fig. 2 is another perspective view taken from a position under the head of the razor.

Fig. 3 is an end elevational view looking at the head of the razor.

Fig. 4 is an elevational view of the handle end of the device.

I claim:

The ornamental design for a razor, as shown and described.

LUCY COTTON.
